UNITED STATES PATENT OFFICE

SAMUEL HORACE WRIGHT DAWSON, OF GAINSBOROUGH, ENGLAND, ASSIGNOR TO
MARSHALL, SONS AND COMPANY LIMITED, OF GAINSBOROUGH, ENGLAND, A BRITISH
COMPANY

TRACTOR

Application filed January 23, 1931, Serial No. 510,809, and in Great Britain June 5, 1930.

The present invention relates to tractors, and more particularly to means for driving the same.

According to the present invention an internal combustion engine in the form of a horizontal two-stroke cycle, Diesel or heavy oil engine is built on the tractor to form an integral part of the frame thereof preferably at the front of the tractor, whilst above and intermediate the ends of the cylinder, i. e., at the rear of the cylinder head a radiator is provided, the said radiator forming part of the cooling system for the engine cylinder and having water passed through it from a pump situated in rear of the radiator.

The invention is more particularly described with reference to the accompanying drawing which shows part of a tractor in side elevation.

The tractor comprises one or a pair of steering wheels 1 and a pair of driving wheels 2 provided with the usual spikes or stakes 3. The driving wheels 3 may be driven directly from a driving axle 4 or through differential gearing 5 from a selection speed transmission gearing 6 driven from the main driving shaft of a two-stroke Diesel engine 7, which preferably forms part of the frame of the tractor. This engine is preferably of the single cylinder type, but may also be two or multi-cylindered. The head 8 of the cylinder or cylinders is detachable and forms part of a water circulating system, including a radiator 9 mounted directly on the cylinder to allow for full access and detachability of the head 8.

The cooled water from the radiator 9 passes downwards into a chamber 10 surrounding the engine and thence through the cored passage 11 in the detachable head from whence it passes through a tube 12 inserted through the water jacket or chamber 10 of the engine and lying horizontally above it throughout its length, being connected at its rear end by pipe connection 13 to a pump or impeller 14 driven through bevel gearing 15 from a friction wheel or the like driven from the crank shaft of the engine. This pump 14 assists in maintaining vigorous circulation of the water through flexible connection 16 to the header 17 above the radiator 9.

The engine preferably is started by means of an ignition cartridge which is first of all ignited and then inserted in the engine cylinder.

Preferably also whilst it may be at any reduced pressure starting is effected at half compression, i. e. at a pressure between 200-300 lbs. per square inch, and in this way a much smaller flywheel may be used than would be the case in the event of starting at full compression, with the result that starting by hand is rendered easier.

Where reference has been made to Diesel or heavy oil engine, this is regarded as meaning an engine normally running with a compression high enough to ignite the fuel as distinct from a hot bulb or surface ignition engine.

I declare that what I claim is:—

A tractor comprising a frame-work including as integral parts thereof the cylinder of a heavy oil engine, driving and steering wheels supporting said frame, a detachable head for the cylinder of said engine having water passages therein, a water jacket for the engine, a radiator mounted on said water jacket to the rear of and independent of said detachable head, a water circulation pipe disposed through said water jacket, a circulating water pump, a pipe connection from said pump to said circulation pipe and a pipe connection from said pump to said radiator.

In witness whereof, I have hereunto signed my name this 27th day of November 1930.

SAMUEL HORACE WRIGHT DAWSON.
